No. 1349.

b. j. Woolson.
Design for Door Plate.

Patented Dec. 4, 1860.

Dec. 13 49

Charles J. Woolson, of Cleveland Ohio.
Letters Patent No. 1349, dated Dec. 4, 1860.

The schedule referred to in these Letters Patent and making part of the same.

To all whom it may concern:

Be it known that I, Charles J. Woolson, of Cleveland, Cuyahoga Co., Ohio, have invented and produced a new and useful design for the front plate of a Franklin Stove; and I hereby declare that the following is a full and exact description thereof; reference being had to the accompanying drawing, in which my ornamental design is clearly represented: The shape and configuration of the plate is designated by the general outline of the drawing.

2

Des. 1349

The ornament around the inside of the Stove front is seen at A.A.

The ornament around the outside is seen at B.B. The centre ornament at C. The corner ornament at D.

Having thus distinctly represented and described the nature and arrangement of the different ornamental work upon the Stove Front: what I claim therein as new, and desire to secure by Letters Patent, is, the configuration and arrangement of said ornaments as herein designated and represented.
